DEVICE FOR HANDLING ARTICLES

Earl Hart, Downers Grove, Ill., assignor to
 Western Electric Company, Incorporated, New
 York, N. Y., a corporation of New York

Application May 10, 1939, Serial No. 272,737

1 Claim. (Cl. 211—13)

This invention relates to a device for handling articles, and more particularly to a device for conveying irregularly shaped articles, such as handset telephone parts in the process of being manufactured.

Objects of the invention are to provide a simple, inexpensive and compact device for handling articles.

In accordance with the above objects, one embodiment of the invention contemplates the provision of a carrier particularly suitable for conveying handset telephone parts in the process of being manufactured, the said carrier comprising a hollow frame having a pair of spaced side walls, each adapted to support on its outer surface a row of telephone handles, and a pair of trays removably supported between the two walls for carrying telephone transmitter and receiver caps.

A more complete understanding of the invention and the novel features thereof may be had from the following detailed description when read in conjunction with the accompanying drawings, in which

Fig. 1 is a side elevational view, partly in section, of an article carrying device embodying the invention;

Fig. 2 is a vertical sectional view on line 2—2 of Fig. 1, and

Fig. 3 is an elevational view showing several of the carriers suspended from an overhead conveyor chain.

Referring to the drawings, the carrier device illustrated therein comprises a hollow frame 10 of substantially U-shaped cross-section. The frame is preferably composed of two identical side wall sections 11 and 12 having converging lower portions 13 and 14, respectively, which are formed with downwardly projecting ears 16, 16 for accommodating bolt and nut assemblies 17, 17 by means of which the two sections are rigidly clamped together, as shown in Figs. 1 and 2. Each of the side walls has a horizontal arm 19 projecting inwardly from its upper portion, and the inner ends of the arms 19 of the two walls overlap each other and are spaced apart just sufficiently to loosely accommodate therebetween the lower end of a vertical suspension strap or hanger 20, to which the carrier is pivotally attached by means of a bolt and nut assembly 21. The hanger 20 serves as a means for pivotally suspending the carrier from an overhead conveyor. As shown in Fig. 3, a plurality of carriers may be pivotally suspended from equidis-

tantly spaced links of a conveyor chain 22, only a portion of which is illustrated.

The upper edge of each of the side walls 11 and 12 of the carrier frame is formed with a plurality of spaced U-shaped notches 24, 24 (Fig. 2), there being four such notches in each side wall in the illustrated embodiment of the invention. Each of the notches is adapted to receive the semi-spherical transmitter end portion of a telephone handset handle 25, whereby the carrier is adapted to hold eight handset handles, four on each of the two side walls 11 and 12, as shown in broken lines in Figs. 1 and 2. It will be noted that the handles hang on the outside of the carrier walls and that the notches 24 are spaced apart so that the handles are separated from each other. This eliminates frictional contact of the handles with each other, which might cause damage to their finished outer surfaces.

Two trays 26, 26 are removably supported, one above the other, in the space between the two side walls 11 and 12 of the carrier frame. The lower tray is slidably supported upon the converging side wall portions 13 and 14, which are formed at each end with retaining flanges 27, 27 for preventing accidental endwise displacement of the tray. The upper tray is slidably supported upon inwardly projecting shelf-like portions 28, 28 of the side walls, and the portions 28 are formed at each end with retaining flanges 29, 29 for preventing accidental endwise displacement of the upper tray.

Each of the trays is adapted to contain a plurality of telephone receiver and/or transmitter caps 30, 30, which are arranged in the trays in a horizontal row, as shown in broken lines, in Figs. 1 and 2. Each tray is provided with an outwardly projecting horizontal flange 32 at each end thereof, whereby either end of either tray may be lifted above the retaining flange 27 or 29 and withdrawn from the corresponding end of the carrier frame, as shown in broken lines in Fig. 1. In other words, either tray may be withdrawn from either end of the carrier frame and, therefore, is conveniently accessible for loading and unloading from either side of the conveyor chain.

The side walls of the carrier frame are provided with suitable slots or openings, as shown, through which an operator may readily see whether or not either of the trays is filled with caps. The slots also serve to reduce the weight of the carrier frame. Similar weight reducing slots are provided in the walls of the trays. The

trays, as well as the two walls comprising the carrier frame, are preferably constructed so that they may be readily molded or cast from aluminum, thus providing a carrier of light weight and durable construction.

It is to be understood that the invention is not limited to the structural details herein illustrated and described, except insofar as is defined by the appended claim.

What is claimed is:

A carrier for telephone parts comprising a U-shaped hollow frame having spaced vertical walls

formed with notched upper edges for retaining in spaced apart relationship a plurality of telephone parts suspended from said notched upper edges and arranged in oppositely disposed rows 5 on the outer surfaces of said walls, said frame having portions for engaging and maintaining the lower ends of the two rows of suspended parts in spaced apart relationship and additional inwardly directed portions for removably supporting additional parts between said rows.

EARL HART.
